RADIATOR COVER

Albert E. Blackman, Mount Vernon, N. Y.

Application August 3, 1931. Serial No. 554,795

15 Claims. (Cl. 237—79)

This invention relates to covers or enclosures for radiators such as are used for the steam and hot water heating systems for buildings. Owing to their extreme bulk, the shipment of radiator covers when completely assembled is a troublesome problem. It is an object of the present invention to produce a cover of such construction that it is readily knocked down for shipment in small bulk. It is a further object to construct the cover so that ordinary unskilled persons can quickly assemble it. A still further object is that the construction is such that once assembled a very rigid and strong radiator cover is obtained.

Other objects and advantages will become apparent upon a further study of the description and drawings, in which:

Fig. 1 is a perspective view of the radiator cover.

Fig. 2 is a broken vertical cross section, to an enlarged scale, of the cover taken along the line 2—2 of Fig. 4.

Fig. 3 is a broken top view of the cover with the parts shown separated.

Fig. 4 is a plan of the cover with a portion of the top broken away.

Fig. 5 is a sectional plan, to an enlarged scale, through one end of the cover, showing the final position of the end in dotted lines and its position while being inserted in full lines.

Fig. 6 is a partial sectional plan through the cover taken along the line 6—6 of Fig. 2.

Fig. 7 is a partial longitudinal section taken along the line 7—7 of Fig. 6.

Fig. 8 is a partial perspective view from the inside to an enlarged scale of one of the ends of the cover and

Fig. 9 is a partial rear elevation of the cover to an enlarged scale showing the detail of the support at the bottom of the back.

The cover comprises a top 10, two ends 11, a front 12 and a back 13, all of which can be separated from each other and readily assembled again.

Ends 11 are each provided with a bent plate guide 14 spot welded to the web 15, providing V grooves with said web into which the side flanges 16 of the front 12 can be inserted. In addition to flanges 16, front 12 is provided with a top flange 17. Flange 17 acts as a stop to prevent downward sliding of front 12 when inserted in the V grooves formed by guides 14. Top flange 17 and bottom flange 18 act as struts between ends 11 as well as to stiffen front 12.

Flanges 16 of front 12 are inserted behind guides 14, by holding ends 11 at an angle considerably less than 90 degrees with front 12 as

shown in solid lines for one of the ends in Fig. 5. Once front 12 is inserted in ends 11, the latter are spread to 90 degrees with said front, and back 13 is placed between the rear flanges 19 of said ends. Back 13 is provided with bent plate guides 20 which are preferably spot welded to it. Flange 19 fits in the V groove formed between guide 20 and the rest of back 13. The top of guide 20 is sufficiently below the top flange 21 of back 13, (Fig. 2) to permit top flange 22 of the end 11 to clear said guide when back 13 is placed in position on flanges 19. A stamped out tongue 23 (Figs. 3, 8 and 9) is provided on flange 19 to support the bottom of back 13 which is provided with a notch 24 for engagement with said tongue. Top flange 21 of back 13 is provided with a downwardly extending lug or key 25 at each end (Fig. 3). Corresponding to keys 25, top flanges 22 each have a slot 26 for engagement with said keys. When back 13 is placed in position, flange 21 comes above flanges 22 and keys 25 enter slots 26 from above, locking ends 11 together.

The top of ends 11, at the front, is provided with a spacing piece 27, best seen in Figs. 2 and 3. Piece 27 has flange 29 extending downwardly at the front and another flange 28 extending downwardly at the side of the cover. Flange 29 is offset forwardly of end 11, while flange 28 is offset laterally from the web 15 of said end. The purpose of this is so that when top 10 is put in place, its downwardly extending flanges will come over flanges 28 and 29 and hold said top in offset position from the rest of the cover, both forwardly and laterally.

Top 10 has an asbestos filler 30 held in place by clips 32, two of which are shown in Fig. 3.

Referring now to Fig. 5, it will be noted that flange 16 makes an angle of less than 90 degrees with the front face of the cover. Now when ends 11 are forced apart, and back 13 inserted between them, flange 16 is sprung into a right angle with the front of the cover, giving rise to an internal stress in the cover. This produces a very stiff and tight cover. It is preferred to make flange 16 less than 90 degrees with the front, but the same effect of stiffness can be obtained if the front flange 31 of the end 11 instead were made less than 90 degrees with its web 15. When ends 11 are forced apart, springing flange 31 to 90 degrees would provide the necessary internal stress in the cover. While 90 degrees is the preferred angle, it is readily understood that another angle will do, so long as flange 31 must be sprung from said latter angle when the back is placed between the ends.

It is to be noted that front flange 31 is folded back on itself.

Once ends 11 are mounted on front 12 and spread apart at their rear for the mounting of back 13, they are interlocked with front 12. On the other hand back 13 would only remain in position on the ends because of the springing action of the front mounting of the ends. Because of this, positive locking means, such as keys 25 and slots 26, are provided for the mounting of the back 13.

I claim:—

1. A radiator cover having a top, front, back and ends all removable from each other, a guide piece fastened on the inside of each end towards its front edge, each guide piece with its corresponding end forming a guide groove open toward the front, and a rearwardly extending flange at each end of the front adapted to enter said groove 20 for fastening the ends to the front.

2. A radiator cover having a top, front, back and ends all removable from each other, a guide piece fastened on the inside of each end towards its front edge, each guide piece forming with its corresponding end a guide groove open toward the front, said front having rearwardly extending top, bottom and end flanges, said end flanges entering said groove when the ends are mounted on the front, the top flange coming above said 30 guide pieces and the lower flange below.

3. A radiator cover having a top, front, back and ends removable from each other, resilient means for holding the ends to the front, and means for fastening the back to the ends, said 35 resilient means being flexed when the back is fastened to the ends.

4. A radiator cover having a top, front, back and ends removable from each other, resilient means for holding the ends to the front, said 40 means normally holding the ends at a predetermined angle to the front and means for fastening the back to the ends, said ends requiring spreading at the rear from said predetermined angle for the fastening of the back to the ends, 45 said spreading causing said resilient means to be flexed.

5. A radiator cover having a top, front, back and ends removable from each other, a guide piece fastened on the inside of each end towards 50 its front, each guide piece forming with its corresponding end a guide groove open toward the front, a rearwardly extending flange at each end of the front adapted to enter said grooves for fastening the ends to the front, and an inwardly extending flange at the front edge of the end coming in front of the front when said end is fastened in position on the front.

6. A radiator cover having a top, front, back and end members removable from each other, a 60 guide piece fastened on the inside of each end member towards its front, a rearwardly extending flange at each end of the front, said flanges engaging said guide pieces when the end members are mounted on the front, a guide piece 65 fastened to the inside of the back at each end of the back, and an inwardly extending flange at the rear of the end members engaging with said latter guide pieces when the back is placed in position on the end members.

7. A radiator cover having a top, front, back and end members removable from each other, a guide piece fastened on the inside of each end member towards its front edge, a rearwardly extending flange at each end of the front, said 70 flanges engaging said guide pieces when the end

members are fastened to the front, a guide piece for each end member fastened to the inside of the back near each end of the back, each guide piece forming with the back a guide groove open towards its corresponding end, and an inwardly extending flange at the rear of the end members extending into said guide grooves when the back is placed in position on the end members. 80

8. A radiator cover having a top, front, back and end members removable from each other, means for mounting the front upon the end members said means normally holding the rear ends of the end members too close together for the mounting of the back upon said end members, said means interlocking the front with the end members when said end members are spread apart sufficiently for the mounting of the back thereon; means for mounting the back upon said end members when spread apart from said normal distance, and locking means for locking the back to the end members. 85

9. A radiator cover having a top, front, back and ends detachably mountable together, inwardly projecting top and front flanges on each end member, rearwardly projecting top and end 100 flanges on the front, and a guide piece fastened on the inside of each end member towards its front edge extending for a substantial part of the height of said end member the top of the guide piece being located a distance below the 105 top flange of said end member, said rearwardly extending end flanges of the front engaging said guide pieces when the end members are attached to the front, the top flange of the front entering the spaces between the top of the guide pieces 110 and the top flange of the end pieces.

10. A radiator cover having a top, front, back and end members removable from each other, means for detachably holding the ends to the front, inwardly projecting top and rear flanges 115 on each end member, a forwardly projecting top flange on the back, and a guide piece mounted on the inside of the back near each end of the back extending for a substantial part of the height of said back the top of the guide piece being located a distance below the top flange of the back, the rear flanges of the end members engaging with said guide pieces when the back is in position on the end members, the top flanges of the end members entering the spaces between the 125 top of the guide pieces and the top flange of the back.

11. A radiator cover as claimed in claim 10 in which the top flange of the back is provided with a downwardly projecting key near each end 130 thereof and the top flange of each end member is provided with a slot engaging said key, whereby the end members are locked together by the top flange of the back.

12. A radiator cover as claimed in claim 10 in 135 which the top flange of each end member is provided with a slot near its rear, and the top flange of the back is provided with a downwardly projecting key near each end thereof engaging said slot, whereby the end members are locked together by the top flange of the back. 140

13. A radiator cover as claimed in claim 10, and means on the rear flange of each end member holding the bottom of the back to said flange.

14. A radiator cover as claimed in claim 10, 145 and an upwardly projecting tongue on the rear of each end member engaging corresponding notches provided in the bottom edge of the back.

15. A radiator cover having a top, front, back and end members removable from each other, 150

means for mounting the front upon the end members, said means normally holding the rear ends of the end members too close together for the mounting of the back upon said end members, said means interlocking the front with the end members when said end members are spread

apart sufficiently for the mounting of the back thereon and means for mounting the back upon said end members when spread apart from said normal distance.
